UNITED STATES PATENT OFFICE

THEODORE BIRKENMAIER, OF ST. LOUIS, MISSOURI, ASSIGNOR TO W. N. MATTHEWS CORPORATION, OF ST. LOUIS, MISSOURI, A CORPORATION OF MISSOURI

ANCHOR

Application filed June 30, 1927. Serial No. 202,531.

This invention relates to anchors and with regard to certain more specific features, to ground anchors such as are used for holding guy wires and the like.

Among the several objects of this invention may be noted the provision of an improved and more compact expanding ground anchor adapted to be opened by the application of blows from a separate tool; the provision of an anchor of the class described, having expanding flukes adapted to be positively locked in their expanded holding positions; the provision of an anchor of the class described incorporating in its construction the combined advantages of simplicity of operation and construction, ruggedness of finished product, a minimum number of working parts, and economy.

Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings, in which are illustrated two of various possible embodiments of the invention,

Fig. 1 is an ideal side elevation, partly in section, of an assembled anchor shown within a hole, the anchor being shown in a retracted solid-line position and a dotted-line locked and expanded position;

Fig. 2 is a plan view of the anchor in expanded position;

Fig. 3 is a perspective view showing one of the flukes of the anchor;

Fig. 4 is a partial side elevation of a modification, shown closed;

Fig. 5 is a plan view showing the modification open; and

Fig. 6 is a side elevation of one of the modified flukes, showing an alternative position in dotted lines.

Corresponding reference numerals indicate corresponding parts throughout the several views of the drawings.

Referring now more particularly to Fig.

1, there is illustrated at numeral 1 a round or similar hole which is dug into the ground in the usual manner for the placement of anchors of the general class herein described. The general contour of the present anchor, before expansion, is round so that it may fit this hole more or less properly but it is to be understood that it may be square or of other suitable contour. The anchor is adapted to hold a tie rod 3 in place, said tie rod being of the class adapted to be coupled to guy wires or the like.

Referring to both Figs. 1 and 2, the numeral 5 indicates a more or less flat circular body portion or collar having an opening 7 through its center, the opening being used to slidably receive the shank of said tie-rod 3. Cast integrally around the circumference of said body or collar 5 are a plurality of pairs of projecting ears 9. It is understood that the number of these pairs of ears need not be definitely set at five, but, for the purposes of illustration, this number is used throughout this description. On an axis through each of these pairs of ears are holes 11 adapted to carry a bolt 13 which, with the aid of a retaining cotter-pin 15, holds a fluke 17 so that it is pivoted radially on this bolt. Both the top and bottom of said collar 5 are substantially flat.

At the end of the tie-rod 3 is placed a spreader disc or plate 19 through the center of which is formed a hole 21. The tie-rod passes loosely through this hole. The tie-rod 3 is also threaded at its lower end, and a nut 23, screwed on to this tie-rod, prevents the spreader disc 19 and the collar 5 from slipping from the end of the rod. The spreader disc 19 has formed in its bottom a recess 25 adapted to accommodate the nut 23. The edges of disc 19 are rounded, and the top is partly hollowed out, as is shown by the cross-section in Fig. 1, that is, a camming lip 18 is formed.

The flukes 17 (see Fig. 3) comprise primarily a comparatively arcuate shaped spade portion 27 and a central rib 29 formed at right angles to and on the convex side of the spade portion 27. The purpose of this mid-rib 29 is to provide a support for the spade

portion 27 and in addition to provide a means for camming or moving the flukes 17 with respect to the part 5. As can be seen in the drawings, said mid-rib has a cam-shaped edge 31, the purpose of which will be explained hereinafter. At its upper edge said mid-rib 29 is provided with a notch 33 and at the very top it is circular in shape. A hole 35 is formed in the circular portion, through 10 which passes said bolt 13 for movably affixing the fluke to the collar 5.

The operation of the anchor, is as follows:

15 The tie-rod 3 is placed through the holes 7 and 21 in the collar 5 and spreader disc 19 respectively, in the order named. Nut 23 is affixed to the end of the rod 3 so that collar 5 and disc 19 cannot slip off the rod. Said disc 19 and collar 5 are then separated to such a distance that flukes 17 are in a retracted 20 position (as shown in solid lines in Fig. 1). Collar 5 and disc 19 should not and cannot be placed far enough apart so that the outer edges of the flukes will rest upon the top of the disc 19, because the noses 34 at the notches 33 prevent it. The result is a positive alignment 25 of the flukes. In this position the flukes are secured by tying them with a piece of twine or wire 37. This is done to keep the flukes in their retracted and aligned position, until the anchor is placed in the hole 1. The twine or wire can be easily broken. The tying procedure is not absolutely essential to the operation of the device.

30 The anchor is next placed in the hole 1 in the earth. It will assume a position shown in Fig. 1, (solid lines). A tool 39 is then hammered upon the upper surface of collar 5. A sharp blow is sufficient to break the retaining twine or wire 37 after which the flukes are forced outward as a result of the action of the blows combined with the action 40 of the edge of disc 19 on the cam surface 31 of the flukes. Little force is needed to drive 45 the flukes into the earth and repeated blows with the tool 39 drive the flukes farther into the earth.

Finally, as the tamping or hammering continues, the flukes are driven so far apart that 50 the edge 18 of disc 19 has reached the end of the cam surfaces 31. Another single blow suffices to carry the edge of the disc past the cam surface and lie in position to be engaged by the notches 33, as soon as a slight upward 55 pull is given to the tie-rod 3. In this manner the flukes lock themselves in an opened position, securely anchored in the earth. The hole 1 is now filled, and the guy wire affixed to tie-rod 3.

60 In Figs. 4 to 6 is shown a modified form of the invention having certain improved features. Referring to Figs. 4 and 5 it may be seen that this form comprises a collar 41 slidably supported on the anchor rod 3 and 65 carrying sets of ears 43, similar to the ears 9,

to which are pivoted five flukes 45. As in the previous form, the lower end of the anchor rod 3 carries a disc member 47 for engaging camming surfaces 49 on the bottoms of the flukes (see also Fig. 6).

70 The upper surfaces of the flukes are provided with webbing 50 for strengthening purposes. One of the advantages of the modified form rests in the fact that the flukes are given a curvature as illustrated at 51, 75 whereby, when said flukes are driven from their solid line position (Fig. 6), to their dotted line position, they take a path which is of such shape that each fluke is forced into the ground with minimum effort. This is 80 because the leading edge 53 of each fluke cuts a path in the earth into which the successive portions of said fluke place themselves, instead of pushing the earth aside with a component of sideward thrust. This shape of fluke is also desirable, because it provides a better grip in the soil after the anchor has been placed, inasmuch as the curvature is 85 concave upward. Also the holding properties of the soil are not weakened by the fluke 90 tearing and crushing said soil.

95 The modified form of fluke is also provided with a notch 55 for engaging the disc 47 in locking position when the anchor is open.

100 The flukes 45 of the modified form are also provided with re-entrant edges 57 having an irregular contour such that juxtaposed edges of successive flukes on the anchor will intermesh to provide as small a 105 closed anchor core 59 as it is possible to get with the given amount of expansion. The edges 57 consist of projections 61 and bights 63 so arranged that a projection on one fluke intermeshes with a bight on the juxtaposed fluke when in closed position. The shapes 110 of the projections and bights are such that no interference is had during the closing and opening operations. It will be seen from the drawings that on each fluke a bight on one edge is located opposite a projection on the other edge. It is apparent that by this 115 means it is possible that all flukes on a single anchor have substantially the same shape so that they may all be formed from a single pattern.

120 It is also to be noted that the advantages of the small closed anchor may be attained by special shapes on the fluke edges which will engage to permit the formation of a substantially closed, hollow bell shape when the flukes are closed (Fig. 4), juxtaposed fluke edges effecting closure, as in the example set out above.

125 Another novel feature of the modified form, which may also be used in conjunction with the first form is that the rivets 65 which loosely pass through the ears 43 and hold the flukes in position are of such length that the tail or body 67 of each one interferes 130

with the head 69 of the next one when they are in the relative positions shown in Fig. 5. Hence the rivets cannot fall out, though only one cotter key 71 is used in one of the rivets. 5 This is because the cotter key 71 retains the one rivet in such position that its tail prevents substantial movement of the next rivet and consequently of all the rivets. When the cotter key is removed, all of the rivets 10 may be moved into such positions that they will leave the ears 43 and thereby permit removal of the flukes.

The operation of the modified form is analogous to that of the form hereinbefore 15 described.

It is to be understood that the particular curvature, as indicated by numeral 51, of the fluke shown in Fig. 6 may be applied to the modification shown in Figs. 1 to 3.

20 In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. The anchor comprising juxtaposed pivoted flukes adapted to be opened and closed and re-entrant edges on said flukes adapted 35 to intermesh when the flukes are in closed position.

2. The anchor comprising juxtaposed pivoted flukes adapted to be opened and closed by moving them toward and from a spreader 40 disc, re-entrant edges on said flukes adapted to intermesh when the flukes are in closed position, said flukes having curvatures such that successive portions of the flukes follow substantially in the paths initially cut by 45 their leading edges.

3. In an anchor the provision of a spreader on a shank, a collar movable with respect to the spreader having flukes pivoted thereto adapted to engage said spreader and means 50 for pivoting the flukes comprising pivot members arranged so as to interfere with one another when one is locked in a predetermined position, whereby they cannot be removed and not to interfere when said one 55 pivot member is unlocked.

4. In an anchor the provision of means for pivoting juxtaposed flukes comprising pivot members arranged so as to interfere with one another when one is locked in a predetermined position so that they cannot be 60 removed and not to interfere when said one pivot member is unlocked.

5. The anchor comprising juxtaposed pivoted flukes adapted to be opened and closed, 65 re-entrant edges on said flukes adapted to

intermesh when the flukes are closed, said edges comprising projections and bights.

6. The anchor comprising juxtaposed pivoted flukes adapted to be opened and closed, re-entrant edges on said flukes adapted to 70 intermesh when the flukes are closed, said edges comprising projections and bights, a bight being located opposite a projection on the opposite edge of the fluke on which both are located.

7. The anchor comprising juxtaposed pivoted flukes adapted to be opened and closed, re-entrant edges on said flukes adapted to 75 intermesh when the flukes are closed, said edges comprising projections and bights, a bight being located opposite a projection on the opposite edge of the fluke on which both are located and all of the flukes having substantially the same shape whereby they may be made from a single pattern.

In testimony whereof, I have signed my name to this specification this 16th day of June, 1927.

THEODORE BIRKENMAIER.
